UNITED STATES PATENT OFFICE.

WILLIAM R. WHITEHORNE, OF BROOKLYN, NEW YORK, ASSIGNOR TO EDWARD F. CLEMENTS AND M. BROOK JACOBS, TRUSTEES, OF PHILADELPHIA, PENNSYLVANIA.

ELECTRIC HEATER.

No. 878,919.

Specification of Letters Patent.

Patented Feb. 11, 1908.

Application filed April 22, 1907. Serial No. 369,678.

To all whom it may concern:

Be it known that I, WILLIAM R. WHITEHORNE, a citizen of the United States, and a resident of Brooklyn, Kings county, New York, have invented certain Improvements in Electric Heaters, of which the following is a specification.

One object of my invention is to provide electric heating means for dye vats, which means shall be so constructed as to obviate the possibility of any electrolytic action which might affect the liquor or compounds in the vat.

It is further desired to provide an electric heater which shall be relatively simple and compact in construction and of such a nature as to permit of the convenient regulation of the current passing through it and therefore of the heat produced.

It is also desired to provide a heater for liquids of such a nature as to be capable of operation by alternating currents of electricity and which shall efficiently utilize the energy supplied to it.

These object and other advantageous ends I secure as hereinafter set forth, reference being had to the accompanying drawings, in which

Figure 1, is a vertical section, to some extent diagrammatic, of a dye vat provided with a heater constructed according to my invention; Fig. 2, is a horizontal section on the line 2—2, Fig. 1, further illustrating my invention, and Figs. 3 and 4, are vertical sections of modified forms of my invention.

In Figs. 1 and 2 of the above drawings, A represents a water tight metallic box or casing of any shape and material desired, though preferably constructed of aluminum. In the present instance I have illustrated this casing as of substantially cylindrical form having on its top, bottom and sides concentric corrugations *a* and on its sides other corrugations, whereby the external surface of the casing is materially increased. While I have illustrated this outside surface as corrugated, it will be understood that other means or surface configuration may be employed for increasing the heat dispersing surface of the device. A dye vat F of any desired construction is shown as containing the casing A which is placed upon the bottom of said vat under the perforated partition *f'*.

Inclosed within the casing A is a laminated iron ring or core B having a number of coils each consisting of a relatively large number of turns of wire *b* as indicated, forming the primary winding of a transformer of which the secondary is formed by the metal of the casing A and by a metal core *a'* of copper or aluminium extending concentrically through the ring B and electrically connected to the casing so as to form a closed electric circuit of low resistance therewith. For convenience of construction I make the cover *a²* removable from the body of the casing A, holding it in its normal position by means of a bolt *a³*.

A pipe *a⁴* extends upwardly from the casing A for the purpose of permitting the entrance of current supply wires for the primary winding, and in order to control the operation of the device, I provide a single wire *a⁵* connected to one of the supply mains and to one terminal of each coil *b*. The second ends *a⁶* of the said coils I bring out through the pipe *a⁴* to a multiple point switch *a⁷* connected to the second supply main and constructed so as to permit of any desired number of the coils *b* being thrown into circuit.

The interior of the casing A, after the introduction of the ring B and its winding, is filled with oil so as to not only increase the insulation but also aid in conducting of heat from the interior of the structure to the outer portions thereof. Under operating conditions, when its windings *b* are connected to a suitable source of alternating current, a current is induced thereby in the body of the casing A and its core *a'*, thereby generating heat and raising the temperature of any liquid in the dye vat to the extent desired; the device acting as a transformer with a short circuited secondary having but a single turn in which a current of any desired magnitude may be induced, depending upon the design of the device and upon the voltage of the current supplied to the primary winding *b*.

The large current so induced in the core *a'* and the casing, rapidly heats the same and inasmuch as the current supplied to the primary winding may be controlled within any desired limits by means of the switch *a⁷*, it is obvious that the amount of heat generated may be likewise controlled with the greatest exactness.

It is obvious that the device may be designed so that the voltage of the current re-

quired to be supplied to the primary windings b may be relatively low while the voltage induced in the metallic casing is naturally many times lower. As a result there is no difficulty in insulating the device so that leakage of the current is effectually prevented. Moreover, there can, with such an arrangement of parts, be no possibility of electrolysis or electrolytic action in the dye liquor. The pipe a^4 through which the conductors pass into the casing may under certain circumstances permit of the escape of surplus oil in case the temperature should be such as to cause undue expansion or boiling of the oil contained in the casing.

In Fig. 3, I have shown a form of my invention in which the vat F' itself is of metal and so constructed as to constitute a portion of the electric circuit of the transformer whose core is provided by a metallic bar b^2 which may be laminated if desired. This core is surrounded by a coil of wire b' forming the primary winding of the device and inclosed by a suitable casing b^3 so as to be kept from contact with the liquid in the vat. The cover f^2 is removable, being provided with eye bolts f^3 to facilitate its handling.

In Fig. 4, the vat F^2 is of wood with a perforated false bottom f^4 below which is placed the electric heater. This latter consists of a metallic tube A' containing a core a^8 and having within it, in the space between the core and its interior walls, a winding b^6 forming the primary of a transformer whose secondary is formed by the tube A' , the core a^8 and suitable end pieces a^9 electrically connecting said tube and core. In any case the action of the device is the same as described in connection with Figs. 1 and 2, for the alternating current supplied to the primary winding induces a large current of very low voltage in the parts constituting the short circuited secondary of the device, which large current causes heating of the parts and consequent heating of the liquid in the vat.

One advantage of the use of aluminium for those parts of the device in contact with the liquid in the vat lies in the fact that this metal quickly becomes coated with a noncorrosive coating of aluminium oxide which effectually prevents any contamination of the dye liquor or injury to the parts themselves.

I claim:

1. An electric heater, consisting of a winding connected to a source of alternating current, and a metallic casing placed in inductive relation to said winding so as to form the short circuited secondary of a transformer of which said winding is the primary, said casing forming a liquid tight envelop completely inclosing said winding, substantially as described.

2. An electric heater consisting of a winding connected to a source of alternating current, a core for said winding, with a liquid

tight casing completely inclosing said winding and forming the short circuited secondary of a transformer of which said winding is the primary, substantially as described.

3. An electric heater consisting of a liquid tight metallic casing having a central core connecting its top and bottom, with a winding in the space between said core and the outside walls of the casing arranged to be completely inclosed by said casing, said winding being connected to a source of alternating current, substantially as described.

4. An electric heater consisting of a liquid tight metallic casing forming the secondary of a transformer, a winding therein, having a metallic core and connected to a source of alternating current, and a body of insulating liquid contained within the casing, substantially as described.

5. An electric heater, consisting of a liquid tight metallic casing having its exterior provided with projecting portions forming a relatively extended surface, a central core completely inclosed within the casing, and a winding in the casing having a core and connected to a source of alternating current supply, substantially as described.

6. An electric heater consisting of a winding connected to a source of alternating current, with a body of metal formed in the shape of a liquid tight casing and inductively placed, relatively to said winding so as to completely inclose all lines of force set up thereby and have a relatively large current of low voltage induced in it when an alternating current is applied to the winding, substantially as described.

7. An electric heater consisting of a winding connected to a source of alternating current, with a body of metal forming a casing and inductively placed relatively to said winding so as to have a large current of low voltage induced in it when an alternating current is supplied to the winding, with an insulating liquid in the casing, and means permitting the escape of a portion of such liquid in the event of an abnormal rise of temperature, substantially as described.

8. The combination of a container with an electric heater, said heater consisting of a winding connected to a source of alternating current, and a body of metal formed as a liquid tight casing completely inclosing said winding, said casing being constructed to prevent access of liquid in the container to any space having magnetic flux, when current is supplied to the winding, substantially as described.

9. An electric heater consisting of a metallic casing forming the secondary of a transformer, a closed circuit core of magnetic material within said casing and a winding or windings on said core also in the casing and forming the primary of the transformer, substantially as described.

10. The combination of a metallic casing having a central core and forming the secondary of a transformer, an annular body of magnetic material within the casing substantially concentric with said core, and a winding on said annular body forming the primary of the transformer.

In testimony whereof, I have signed my name to this specification, in the presence of two subscribing witnesses.

WILLIAM R. WHITEHORNE.
